Inventor

Alfred Theriault,

By Clarence A. O'Brien.

Attorney

UNITED STATES PATENT OFFICE.

ALFRED THERIAULT, OF DETROIT, MICHIGAN.

CASTER.

Application filed November 2, 1926. Serial No. 145,795.

This invention relates to an improved 55
caster and attaching means therefor which is
adapted to be used with various articles of
furniture and the like, but which is particu-
larly constructed in the present instance for
use in association with a wardrobe trunk.

The alleged novelty of the improved struc-
ture is directed more particularly to a means
for permitting separable connection of a
10 roller bearing swivel caster wheel to the
trunk, although the means for facilitating
such connection with the trunk constitutes
a feature of novelty.

Briefly, the device which serves as a car-
rier for the caster per se, is in the form
15 of a novel metal stamping which is bent up
and formulated to provide a hollow attach-
ing box, so constructed as to permit removal
and replacement of a novel connecting bolt
20 which serves to mount the box on the trunk.

Other structural features of the invention,
will become apparent from the following de-
scription and drawings.

In the drawings:-

25 Fig. 1 is a side elevation of a wardrobe
trunk equipped with casters constructed in
accordance with the present invention.

Fig. 2 is a bottom plan view of the same.

Fig. 3 is an enlarged side elevation of one
30 of the devices.

Fig. 4 is a sectional view at approxi-
mately right angles to Fig. 3.

Fig. 5 is a horizontal section through the
mounting box.

35 Fig. 6 is a fragmentary bottom plan view
showing the trunk with the caster removed,
and the attaching bolt placed.

Fig. 7 is a view in section and elevation,
showing the manner in which the separable
40 connection between the box and bolt is made.

Fig. 8 is a plan view of the improved metal
stamping.

In the drawing, the reference character 1
designates the wardrobe trunk which is pro-
45 vided on its bottom and adjacent its four
corners, with four of the devices. By di-
recting attention to Fig. 4, it will be seen that
the bottom 2 of this trunk is provided on
50 its inner side with a recess adapted to ac-
commodate the depressed central portion 3
of an inner plate 4. Secured to the bottom
or under side of the bottom, is a similar but
flat plate 5, the two plates being riveted in
place, and both of them being provided with

aligned holes which register with a bored hole 55
in the bottom 2.

The improved attaching box is generally
represented by the reference 6. It is for-
mulated from stamping shown better in Fig.
8. Referring to the last named figure, it 60
will be seen that the stamping embodies a
central bottom conforming portion 7, a pair
of duplicate sides 8, a pair of duplicate top
portions 9, and connecting flanges 10. The
portions 9 are notched at 11 to provide ex- 65
tensions 12.

In making up the box, the sections 8 are
bent upwardly at right angles on the fold
lines represented. Then, the top forming
portions are bent inwardly toward each other 70
to extend in spaced parallelism with the first
portion 7. The extensions 12 are bent in-
wardly toward the portion 7 and at right
angles to the complementary portions 9. The
flanges 10 are also bent downwardly at right 75
angles to be connected together. The portion
7 is formed with a central opening 13 and
the parts surrounding this opening is shaped
to provide a channel, or ball race as shown
in Fig. 4. 80

A connecting bolt 14 passes through the
flanges and carries a flat spring 15 having a
downturned extremity located between the
extension 12. The roller or caster wheels
is represented by the reference character 16 85
and this is swivelly mounted on the yoke 17
which is connected to the part 7 of the box
through the medium of a pivot and swivel
pin 18. The roller bearings 19 are inter-
posed between the bight portion of the yoke 90
and are located in the aforesaid ball race
formed in the bottom 7 of the boxing. This
provides a single unit consisting of the caster
swivelly mounted on the specially construct-
ed hollow metal boxing. 95

The boxing is attached to the trunk
through the medium of a bolt 20 through
the holes in the trunk and the plates 4 and
5. A retaining nut 21 is placed thereon and
is located in the pocket or depression 3 as 100
shown plainly in Fig. 4. The head 22 of the
bolt is in the form of a rectangular thin
metal plate which is clamped in place by
the flat spring 15. When thus clamped, it
is maintained against displacement even after
the nut 21 is removed and the bolt is pulled
out. In other words, the bolt is snapped
into place in the boxing, thus making a sin- 105

gle unit of the boxing, the caster, and the bolt. Then the bolt is slipped through the holes which accommodate it and the clamping nut is placed in position.

5 It is desirable, however, to have the bolt removable from the boxing so that it can be replaced in the bottom of the trunk as represented in Fig. 6 in order to close the hole. If it is desired to remove the bolt, this is 10 done as shown in Fig. 7. As here represented, the bolt is simply pressed down against the tension of the spring 15 until the head 22 clears the extremities of the extensions or ears 12. These ears are spaced 15 apart a distance sufficiently to permit the shank of the bolt to be slipped out between them.

With the bolt thus removed, it can be placed back in the openings in the bottom 20 of the trunk and the nut 21 replaced so that it assumes the relationship shown in Fig. 6.

It is thought that by considering the description in connection with the drawings, a clear understanding of the construction and 25 use of the invention will be obtained. Therefore, a more lengthy description, is thought unnecessary.

While the preferred embodiment of the invention has been shown and described, it 30 is to be understood that minor changes coming within the field of invention claimed, may be resorted to. Moreover, while the invention has applied to a wardrobe trunk, it may be understood that it may be employed 35 in various other similar capacities, with equal effectiveness.

Having thus described my invention, what I claim as new is:—

1. In a structure of the class described, a 40 caster, a hollow attaching box therefor, said box being open on one side, a pair of spaced depending ears on said open side, and a flat spring connected to the box and having its free end located between said ears.

2. In a structure of the class described, a 45 substantially rectangular hollow box open on one side, the bottom of said box being formed with a ball race, spaced depending ears on said open side, a spring on the interior of the box having its free end located 50 between said ears, a caster wheel, a yoke connected with said wheel, a swivel and pivot pin connecting said yoke with the bottom of said box, and ball bearings located between said yoke and box, and disposed in 55 said ball race.

3. As a new product of manufacture, a hollow attaching box open on opposite sides, a depending flange on one side, a slot being 60 formed in the top of the box and opening through the edge of the top at the opposite side, spaced depending ears on opposite sides 65 of the slot, a spring on the interior of the box fastened at one end to said depending flange and having its opposite free end portion located in said ears, a bolt having its shank located in said slot, and having a flat head bearing against said ears and held in place by said spring, and a caster swivelly mounted upon said box. 70

In testimony whereof I affix my signature.
ALFRED THERIAULT.
